UNITED STATES PATENT OFFICE.

WILLIAM MEYER, OF CHICAGO, ILLINOIS.

X-RAY APPARATUS.

1,284,144.

Specification of Letters Patent. Patented July 12, 1921.

Application filed May 31, 1918. Serial No. 237,379.

To all whom it may concern:

Be it known that I, WILLIAM MEYER, a citizen of the United States, residing at Chicago, in the county of Cook and State of Illinois, have invented a certain new and useful Improvement in X-Ray Apparatus, of which the following is a full, clear, concise, and exact description, reference being had to the accompanying drawings, forming 10 a part of this specification.

My invention relates to X-ray apparatus. More particularly my invention relates to an improved generator cabinet and transmission apparatus for X-ray tables and the 15 like. The present application is related to my co-pending application Serial Number 237,213, filed May 29, 1918, for an improvement in transmission stands.

In my co-pending application I have described 20 an improved electro-therapeutic table which employs two X-ray tubes. This table unit, comprising the table and tubes is arranged to be movable as an entirety about the laboratory so that it may occupy 25 any desired position. In this and similar apparatus the radiographic tube is supported above the top of the table where its rays can penetrate the body of the patient lying upon the table top and affect a sensitized 30 plate supported in the table top. The fluoroscopic tube is supported below the table top so that its rays can pass therethrough and through the body of the patient and make a 35 visible exposure on a fluoroscopic screen disposed about the table top. Both of these tubes are adjustable relative to the table, and the top thereof may be inclined to place the patient at any preferred angle convenient for making the examination or 40 exposing. The high tension current for energizing these tubes is generated in a transformer or induction coil which is usually embodied in what is termed a generator cabinet. Heretofore this cabinet has been a relatively permanent 45 fixture and the problem has been to transmit the electrical energy from this permanent cabinet to the tubes on the movable X-ray table.

It is not feasible to extend leads directly 50 from the cabinet to the tubes on the table as these leads would be so low as to interfere with the operation of the table from different angles. They, moreover, are difficult to connect with the fluoroscopic tube 55 beneath the table top in a manner to prevent danger of grounding against the frame

of the table. The more prevalent practice is to string an overhead aerial in the laboratory, which is connected to the cabinet and from which leads are dropped to the X-ray 60 tubes on the table. This is undesirable because of the unsightly appearance, the space it takes up and the expensiveness of the construction, as well as the lack of freedom of movement of the stand and tube. It is 65 further desirable that the purchase of the table and cabinet will represent the total expense of the equipment. In a word, I find that there is a demand for a compact, unitary outfit, which demand has so far remained unsatisfied by the art.

In the present invention I dispense entirely with these prior systems of transmission by providing a very compact cabinet which is attachable to the X-ray table where by both the cabinet and table become movable at a unit. I preferably, though not essentially, control the transformer in the cabinet by regulating devices supported on a stand movable independently of the table 75 and cabinet and connected to the cabinet by a flexible cable. Heretofore these regulating devices have formed a part of the generator cabinet, adding much to the bulk thereof, and required the operator to go to the 80 cabinet to make any adjustment. In the present case the disposal of these regulating devices on an independent stand has materially aided in reducing the size of the cabinet. Furthermore this arrangement facilitates 85 the work of the operator as the movable controlling stand enables the operator to regulate the operation of the X-ray tube from any position about the table most convenient for adjusting and manipulating the 90 tube. As a specific improvement I provide a small size cabinet and transmission tower in a single construction. I provide further a switch for switching the current from the fluoroscopic tube to the radiographic tube, 100 or vice versa, and provide a common control for the switch and for the spark gap. This enables the operator to throw the switch and make the proper spark gap adjustment, all at one operation.

The utility of my invention is not limited to the use with X-ray tables, as it may be used with other types of X-ray apparatus as will be apparent from the following detailed description and claims.

In the drawings accompanying this description I have illustrated one preferred

embodiment of my invention to apprise those skilled in the art how to make and use the same.

In the drawings,

5 Figure 1 is a side elevational view of the generator cabinet and X-ray table, showing the controlling stand for the cabinet in perspective;

10 Fig. 2 is a fragmentary elevational view of the cross arm which supports the drop leads extending to the radiographic tube;

Fig. 3 is a rear elevational view of the generator cabinet and transmission tower;

15 Fig. 4 is an enlarged plan view of the generator cabinet; and

Fig. 5 is a fragmentary detailed section showing the connection between the generator cabinet and the X-ray table.

The X-ray table, designated 1 in its entirety, is illustrated with the table top 2 tilted on an incline to show the disposal of the fluoroscopic tube 3. This table is generally similar to that disclosed in my co-pending application, Serial Number 228,104, 25 filed April 12, 1918, patented March 15, 1921, No. 1,371,507, and I shall make a brief description thereof to illustrate the connections and adjustments of the X-ray tubes on the usual X-ray table.

30 The table top 2, for supporting the patient, is adjustably pivoted between the two parallel side frames 18. The table top may be inclined to any preferred angle and locked by a suitable quadrant lock to place the patient at the proper angle for making the exposure.

On the under side of this table top are arranged guide rails for guiding the tube supporting carriage 5. This carriage supports 40 a lead glass shield in which is inclosed the fluoroscopic X-ray tube 3. The tube carriage 5 has extensive movement along its guide rails and affords adjustment of the tube 3 longitudinally of the table top, while 45 a second carriage, supported on the first carriage and movable transversely thereof affords adjustment of the tube 3 transversely of the table top. The manner in which these carriages are adjusted to bring the fluoroscopic tube 3 and fluoroscopic screen 8 in the proper position for making the examination 50 will be readily apparent to those skilled in the art.

The electrodes of the tube 3 have connection 55 with the insulated conductors 9—9 which extend out through brackets 11, depending from the carriage 5 and have eyelets in their ends adapted for connection with the leads 12—12 extending from the 60 generator cabinet 10. The conductors 9 form the terminals of the tube 3 and move with the tube carriages and the table top through their different adjustments.

65 The radiographic X-ray tube 14, inclosed in the usual lead glass shield, is adjustably

supported in the frame 15 which may be adjusted vertically and angularly about the tubular supporting standard 16. The standard 16 is secured to guide members 17 arranged to roll along the guide rails 18 of the 70 table stand, whereby the tube supporting standard may be shifted along the length of the X-ray table. The rays emanating from the radiographic tube 14 penetrate through the object or part of the body and produce 75 a shadowgraph thereof by acting upon a sensitized plate contained in a plate tray supported in guides in the table top 2. After exposure of the plates therein, this tray is withdrawn from the head end of the table top, which corresponds to the elevated end as viewed in Fig. 1.

The extending arms 14' of the tube 14 are connected to drop leads 21 which unwind from the spring reels 22 depending from the 85 cross arm 23. This cross arm is secured in the forked end of an oblique bar 24 of T section which is bolted or otherwise secured to the cap 25 closing off the top of the tubular standard 16. The cross arm 23 is, of 90 course, of wood or some suitable insulation. The spring reels 22 on this cross arm are adapted to have connection through extensible leads with the generator cabinet 10, the details of which I shall now proceed to describe. 95

The cabinet 10 comprises the outer casing 26 which houses the transformer and other generating apparatus, the details of which I shall not describe as they have no pertinent 100 relation to the present invention. A salient feature in the design of this apparatus, however, is its compactness, whereby I am enabled to inclose it in the relatively small compass shown. Conducive to the same end 105 is the disposal of the regulating controls on the stand 27. These regulating controls consisting of the rheostat and switches, broadly designated 28, are mounted upon the inclined top 29 of the stand 27. Current 110 is conducted to the controlling stand 27 through the cable 31 where it is regulated and thence conducted to the transformer in the cabinet 10 through the flexible cable 32. The stand 27 may be constructed in any preferred form and of any preferred material. The legs of the stand are provided with 115 caster wheels 33 to facilitate moving of the stand.

Referring again to the generator cabinet 120 10, the cable 32 enters the cabinet through the insulating panel 34 upon which is mounted the fuse box 35. The casing 26 is provided with a door 36 (Fig. 3) to permit access to the interior thereof. The top 125 37 of the cabinet supports the terminals of the transmission switch which directs the flow of high tension current to either the fluoroscopic tube 3 or the radiographic tube 14. This switch comprises a pair of terminals, 130 38

and 39, centrally disposed on the cabinet top 37, these terminals having connection with the secondary taps from the transformer. A third post 41, alined with the 5 terminals 38 and 39, but having no internal connection with the transformer, carries a fixed spark gap electrode 42 which co-operates with a companion electrode 43 adjustably mounted in the terminal 39. An ammeter 44 is provided between the terminals 38 and 41, in series with the spark gap 45, whereby the current flow in the secondary of the transformer can be determined by shifting the electrode 43 to obtain a 10 charge across the gap 45. The ammeter 44 is preferably pivoted between the terminals 38 and 41 so that it may be inclined to facilitate the reading of its dial. The electrode 43 is guided in a hole in the terminal 15 39 and a collar 46 sliding thereon has a pin 47 which engages in a longitudinal groove 43' formed in the electrode 43. The collar 46 supports a switch arm 48, which consists of a section of round rod secured in the collar 46 at one end and having its other end flattened out to form a disk shaped contact head 49. Another switch arm 48', similarly formed, is pivoted to the terminal 38 through a collar 51. 20

The two switch arms 48 and 48' are held together by a link 52 of hard rubber or other suitable insulation, which is securely fastened to each rod. In one position the switch arms contact with the contact posts 25 54 adjacent the front edge of the cabinet and in their other position they contact with the posts 55 adjacent the rear edge of the cabinet. 30

It will be apparent that the pin and groove 35 construction of the electrode 43 permits reciprocation of the electrode independent of the switch arms 48 to vary the length of the spark gap 45, but upon rotation of the insulating handle 56 the switch arms are thrown from one set of contact posts to the other. 40

The front pair of contact posts 54 are provided with small holes in which are clamped the brackets supporting the spring 45 reels 57. Each bracket has an extending pin or the like. It is from these reels 57 that the leads 12-12 unwind and thus it will be apparent that when the transmission switch is thrown to bring the switch arms 50 upon the tops of the contact posts 54 the flow of electrical energy from the transformer is through the leads 12-12 and conductors 9 to the fluoroscopic tube 3. The rear pair of contact posts 55 have similar 55 holes in which are clamped the ends of the conductors 58, which extend up through the hollow standard 59 to the spring reels 61. The standards 59, which are preferably constructed of wood, are screwed to the cabinet 60 casing 26 by the angle brackets 62. The upper ends of the standards 59 are joined by a wood cross bar 63, which mounts the spring reels 61. The connectors 58 pass out of the hollow standards 59 adjacent the cross bar 63 and make connection with the binding posts 64-64 in the cross bar. The brackets supporting the spring reels 61 have studs or pins which project down into the cross member 63 and contact with the shanks of the binding posts 64. Extensible leads 65 70 unwind from the reels 61 and hook into screw eyes 66 secured in the cross arm 23. The eyes 66 extend into the cross arm and contact with the studs which support the brackets of the reels 22. It will be apparent 75 that when the transmission switch is thrown to bring the switch arms upon the contact posts 55 the radiographic tube 14 will be included in the circuit of the secondary winding of the transformer. 80

It will be noted that the generator cabinet 10 is attached to the X-ray table 1 by spring clips 68 shown in dotted lines in Fig. 1. These clips are screwed to the lower front edge of the cabinet casing 26 and are composed of resilient sheet metal bent to form the upright hook portion and oblique cam face apparent from Fig. 5. When the generator cabinet 10 is pushed up against the head end of the table as shown, these clips 85 cam down under and hook to a cross bar forming part of the supporting stand of the X-ray table. By depressing the oblique ends of the clips 68 with the toe the generator cabinet may be quickly separated from the 90 X-ray table. Caster wheels 69 and 70 on the transformer cabinet 10, the standards 59 and the X-ray table 1 permit easy shifting of the assembled unit. 95

In operation, the generator cabinet is attached to the X-ray table and the leads 12 and 65 are strung to make connection with the fluoroscopic and radiographic tubes respectively. By the operation of the transmission switch either tube may be brought 100 105 into action as desired. The adjustment of the radiographic tube, either by shifting of the supporting standard or rotation of the tube about the standard, is accommodated by the extensible action of the leads which 110 are always retained taut under the tension of their reels. The tilting of the table top and the adjusting of the fluoroscopic tube relative thereto are likewise accommodated by the extensible leads 12. It will be noted 115 that the top of the cabinet 10 is below the level of the table top 2 when the latter is in a horizontal position, and thus there is no possibility of the leads 12 grounding against the frame of the table top. Furthermore, 120 this permits withdrawal and insertion of the plate tray between the standards 59. After locating the combined table and cabinet unit the operator moves the controlling stand 27 to such a position about the table as will en- 125 130

able him to both focus the X-ray tube and vary the intensity of its rays from this one position. The adjusting and shifting of the X-ray tube and the shifting of the plate changer carriage I shall not describe, as these operations are well known in the art and have no direct bearing upon the present invention.

Obviously the fastening devices 68 may be of different form and differently situated for engagement with different types of X-ray tables. I preferably construct the transformer cabinet and the X-ray table as separable units, though it will be apparent that the transformer cabinet may be readily embodied as a unitary part in the X-ray table stand.

I do not intend to be limited to the precise details shown and described.

20 I claim:

1. In combination, an independent X-ray table having an X-ray tube for the same, an independent generator cabinet for supplying electrical energy for an X-ray tube, means for joining said table and said cabinet into a single movable unit, and a plurality of bearing members for facilitating movement of the table and cabinet over the supporting surface.

2. In combination, an X-ray table, and X-ray tube for said table, a generator cabinet for supplying electrical energy to the X-ray tube, said generator cabinet being a unit complete in itself separate and entirely independent of the X-ray table, means for joining said separate complete unit and the table into a single movable unit, and a plurality of bearing members for facilitating movement of the table and cabinet over the supporting surface.

3. In combination, a unitary X-ray table, a unitary generator cabinet complete in itself for supplying electrical energy for a tube or tubes on said table, means for releasably attaching said cabinet to said table whereby both will be movable as a unit, and a plurality of bearing members for facilitating movement of the table and cabinet over the supporting surface.

4. In combination, an X-ray table, a generator cabinet for supplying electrical energy to a tube or tubes on said table, a tower for leading overhead conductors to an X-ray tube mounted above the table, said tower being connected to said cabinet, and means for joining the cabinet and the table into a single movable unit.

5. In combination, a self-supporting X-ray table and tube stand, said stand having a tube thereon, a self-supporting cabinet and transmission tower comprising a cabinet for inclosing generating means for X-ray tubes and a tower for leading the current overhead through said tube, and means to connect the cabinet to the head of the X-

ray stand and means for supplying current from the cabinet to the X-ray tube or tubes mounted on the stand and table.

6. In combination, an X-ray table and tube stand, said tube stand having an X-ray tube mounted above the top of the table, a generator cabinet for supplying electrical energy to the said X-ray tube, said cabinet having an upwardly extending tower or standard, a terminal at the upper end of said tower or standard, a conductor leading from said terminal through the standard to the electrical apparatus within the generator cabinet, extensible leads extending from said terminal to the X-ray tube and means for attaching the cabinet to the table.

7. In combination, an X-ray table, an X-ray tube disposed above the top of the table, a generator cabinet for supplying electrical energy to the X-ray tube, the top of said cabinet being below the level of the table top, an upwardly extending standard secured to the cabinet, a set of connector terminals on the upper end of said standard adapted to have electrical connection with the cabinet, extensible leads extending from said terminals to said X-ray tube, spring take up means for said leads and means for attaching said cabinet to said table whereby both cabinet and table will be movable as a unit.

8. In combination, a self-supporting X-ray table, a self-supporting cabinet and transmission tower comprising a cabinet for inclosing generating means for X-ray tubes, and a tower for leading the current over head, means to connect the cabinet to the head of the X-ray table, a controller mounted in a movable cabinet for controlling the generation of current for X-rays, said controller being connected to the generating cabinet by a flexible cable and being movable to permit of regulation of the current while the operator is standing in proximity to the X-ray tube, at the table.

9. In combination, a unitary X-ray table and tube stand, said tube stand being adapted to carry an X-ray tube above the top of the table, said stand being adjustable along the length of the table, a generating cabinet having means for generating current for said X-ray tube, a transmission tower mounted on said cabinet for leading the current for said X-ray tube overhead, and a movable controlled cabinet connected to the generating cabinet by a flexible cable, said controller cabinet being movable about the table and stand to permit the operator to control the current for the X-ray tube from any point about the table.

10. In combination, a unitary X-ray table having a table top for making X-ray exposures, said table having a tube stand and tube, a unitary generator cabinet for supplying electrical energy to said tube, means for attaching said cabinet to said table,

whereby the said table and cabinet will be movable as a unit, the top of said cabinet being below the level of the table top at all times, so as not to interfere with the operation of the same.

11. In combination, a movable X-ray table having a pivoted table top, an adjustable X-ray stand and tube for the table top for radiographic work guided along the table, an adjustable X-ray tube guided along the lower side of the table top for radiographic work, a self-supporting cabinet and transmission means for generating and transmitting current to either one of the X-ray tubes for all positions of the table top, and a portable controlling device adapted to be moved to any convenient point about the table and controlling leads running from the device to the cabinet for controlling the current supplied to either one of the X-ray tubes while the operator is standing adjacent any desired point about the table.
- 10
- 15
- 20

12. In combination, an X-ray table, X-ray tubes on said table, a generator cabinet for supplying electrical energy to said tubes, said table and cabinet being mechanically connected together to be movable as a unit without disturbing the electrical connections between the cabinet and the tubes on the table, said cabinet having conductors leading from the cabinet to the tubes, and a stand having controlling devices for regulating the operation of said generator cabinet, said stand being movable about said table, and conductors connecting the controlling devices with the generator cabinet.

13. In combination, an X-ray table having an X-ray tube adjustable with respect thereto, a generator cabinet comprising generating apparatus for supplying electrical energy to said tube, and transmission mechanism for transmitting the current to said tube, said table and said cabinet being mechanically joined to be movable as a single unit, whereby the electrical transmitting mechanism remains undisturbed during operations of the table or tube, and a stand independent of said table and said cabinet, said stand being movable about the table and having regulating devices for regulating the operation of said X-ray tube.

14. In combination, a generator cabinet having an upwardly extending standard 55 mechanically connected thereto, a set of connector terminals on said cabinet, a set of overhead connector terminals on the top of said standard and switching means on the cabinet operable to connect either set of 60 said connector terminals with the generating apparatus in the cabinet.

15. In combination, a unitary generator cabinet, a pair of standards extending upwardly from said cabinet, a pair of connector terminals on said cabinet, a second pair

of overhead connector terminals on the standards, a transmission switch on top of said cabinet operable to connect the generating apparatus with either pair of said terminals, said switch comprising a pair of pivoted switch arms and stationary contacts adapted to be engaged by said arms, said contacts having connection with said connector terminals. 70

16. In combination, a generator cabinet, 75
a pair of standards extending upright from
said cabinet, a first pair of spring reels
mounted on said cabinet, a second pair of
spring reels mounted on said standards, a
pair of live terminals on said cabinet, a first 80
pair of switch contacts connected to said
first pair of spring reels, a second pair of
switch contacts connected to said second pair
of spring reels, and switch arms pivoted on
said live terminals and adapted to contact 85
with either pair of said switch contacts.

17. In combination, an X-ray table, a standard adjacent said table, an X-ray tube mounted on said standard, a cross member extending laterally from said standard, connector terminals on said cross member, leads extending from said terminals to said X-ray tube, a generator cabinet attached to the end of said X-ray table, a transmission tower on said cabinet, a set of connector terminals adjacent the top of said transmission tower, leads extending from said connector terminals to the connector terminals on said cross member, a second set of connector terminals on said generator cabinet, leads extending from said second set of terminals to a second X-ray tube beneath said X-ray table, a transmission switch operable to connect either set of said connector terminals with the generating apparatus in said cabinet, and a controlling stand having electrical connection with said generator cabinet but movable independently thereof, said controlling stand having regulating devices for controlling the operation of said generator cabinet. 110

18. A unitary generator cabinet for supplying electrical energy to the X-ray tubes on a movable X-ray table, said generator cabinet being adapted to have mechanical attachment to said X-ray table, and having overhead transmission means for transmitting current to an overhead X-ray tube for all positions of the table or of said tube and having other transmission means for transmitting current to an X-ray tube under the table for all positions of the table or said X-ray tube, and controlling means movable independently of said cabinet and table for regulating the operation of said generator cabinet. 125

19. In combination, a pair of X-ray tubes, a source of current for said tubes, an adjustable spark gap across the source of current, a switch for connecting the source of 130

current to either tube, and a common handle for operating said switch and for adjusting the spark gap.

20. In combination, an X-ray tube, a source of current, an adjustable spark gap across the source, a switch for connecting and disconnecting the source to and from the tube, and a common handle for independently operating the switch and for adjusting the spark gap.

21. In combination, an X-ray tube, a source of current, a switch for connecting and disconnecting said source to and from said tube, said switch being adapted for 15 rotary movement, and an adjustable spark gap across said source, said spark gap being adapted for adjustment axially of said switch.

22. In combination, an X-ray tube, a source of current, a switch for connecting and disconnecting said source to and from said tube, said switch comprising a set of terminals having connection with said source, said switch being adapted for 25 rotary movement about said terminals, and a spark gap between said terminals, said spark gap being adjustable axially of said switch.

23. In combination, an X-ray table having a pivoted table top, a radiographic X-ray tube above the table top, a fluoroscopic tube below the table top said tubes being mechanically guided on suitable parts of the table, a cabinet connected to the table, said cabinet having self-supporting transmission means for supplying current to said X-ray tubes as desired for all positions of the table or table top.

24. In combination, an X-ray table having a pivoted table top, a radiographic X-ray tube above the table top, a fluoroscopic tube below the table top said tubes being mechanically guided on suitable parts of the table, a cabinet connected to the table, said cabinet having self-supporting transmission

45 means for supplying current to said X-ray tubes as desired for all positions of the table or table top, and a movable control device mechanically independent of the table or cabinet, but electrically connected to the cabinet for controlling the current supplied to said tubes.

25. In combination, an X-ray table, an auxiliary apparatus cabinet, a plurality of 50 spring clips attached to an edge of the said cabinet said clips being composed of resilient sheet metal and comprising an upright hook portion and an oblique cam face, a coöperating catch member on the said table 55 adapted to be engaged by the said cam face when said cabinet and the said table are forced together, the said hook portion being then adapted to latch the said catch member, and an extension of the said clips adapted to be engaged by the foot of operator to depress the said clips to release the 60 said table and cabinet.

26. In combination, a pair of structures comprising a table and a cabinet, caster wheels on the said structures to support the same and upon which the said structures 70 may be moved, a spring clip comprising an upright latch portion, an oblique cam face portion, and a lever portion attached to one of the said structures, a coöperating catch member on the other of the said structures, said catch member being adapted to engage the said cam face of the said spring clip when the said structures are forced together to cause said latch portion of the 75 said clip thereafter to snap into engagement with the said catch member to fasten the said table and the said cabinet together, said lever arm member being adapted to be manually depressed to disengage the said table and the said cabinet.

80 In witness whereof I hereunto subscribe my name this 29th day of May, A. D. 1918.
WILLIAM MEYER.
